GUMMED TAPE DISPENSER OR SIMILAR ARTICLE

Theodore H. Krueger, Stratford, Conn.
(% Better Packages, Inc., Shelton, Conn.)

Filed May 31, 1960, Ser. No. 60,777

Term of patent 14 years

(Cl. D74—1)

FIG. 1

FIG. 2

FIG. 3

FIG. 4

FIG. 1 is a side perspective view of a gummed tape dispenser showing my new design;

FIG. 2 is a front elevational view thereof;

FIG. 3 is an elevational view showing the side opposite to that of FIG. 1, a part thereof being shown broken away for convenience of illustration; and

FIG. 4 is a rear elevational view thereof.

The dominant features of my design are shown in solid lines on the drawings.

I claim:

The ornamental design for a gummed tape dispenser or similar article, as shown and described.
